US00D969577S

(12) **United States Design Patent** (10) **Patent No.:** **US D969,577 S**
(45) **Date of Patent:** **** Nov. 15, 2022**

(54) **GARDENING TOOL**

(71) Applicant: **Fiskars Finland Oy Ab**, Helsinki (FI)

(72) Inventors: **Sami Lyytikäinen**, Helsinki (FI);
Mikko Kemppi, Helsinki (FI)

(73) Assignee: **FISKARS FINLAND OY AB**, Helsinki
(FI)

(**) Term: **15 Years**

(21) Appl. No.: **29/765,143**

(22) Filed: **Jan. 6, 2021**

Related U.S. Application Data

(62) Division of application No. 29/653,701, filed on Jun.
18, 2018, now Pat. No. Des. 921,471.

(57) **CLAIM**

The ornamental design for gardening tool, as shown and described.

DESCRIPTION

FIG. 1 is a top perspective view of gardening tool according to our new design, showing a first embodiment;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top perspective view of a second embodiment;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The superimposed areas encased in broken lines illustrate portions of the gardening tool and form no part of the claimed design. The broken lines in the drawings illustrates portions of the gardening tool and form no part of the claimed design.

1 Claim, 10 Drawing Sheets
